United States Patent Office

Des. 212,865
Patented Dec. 3, 1968

212,865

KEYBOARD KEYCAP

Dean C. Bowman, Oklahoma City, Okla., and Mark S. Mazzetti, Phoenixville, Pa., assignors to General Electric Company, a corporation of New York

Filed Sept. 29, 1967, Ser. No. 8,785

Term of patent 14 years

(Cl. D64—11)

FIG. 1 is a left side, top and front perspective view of a keycap for keyboards, showing our new design; FIG. 2 is a right side elevation view of the same; FIG. 3 is a front elevation view of the same; FIG. 4 is a left side elevation view of the same; and FIG. 5 is a rear elevation view of the same.

We claim:

The ornamental design for a keyboard keycap, as shown.
